FUSIBLE LINK

William L. Roessner, Denver, Colo.

Application September 28, 1945, Serial No. 619,219

11 Claims. (Cl. 169—42)

1

This invention relates to fusible links for controlling safety devices such as window and door closing means, fire extinguishers and the like intended to prevent the spread of fire.

In some uses of the device, the fusible link constitutes part of a chain or other restraining or suspending means whereby pull is exerted on the link in opposite directions. In other uses of the device, the fusible link cooperates with means whereby pressure is exerted against the link from opposite directions. These links are known, respectively, as the "pull" and "push" types. Certain forms of links herein shown and described may be used either as the pull or the push type.

The fusible links of my invention comprise two identical elements connected together in superposed relation by means of fusible metal having relatively low melting points. In the prior art may be found a simple embodiment of fusible link consisting of two flat pieces of metal, rectangular in shape, superposed in partially overlapped relation, the non-overlapped portion of each piece being provided with an aperture for receiving a hook or the like, and the overlapped portions being connected together by fusible solder. When the fusible solder melts under influence of heat and pull is being exerted on the elements, said elements separate by movement in opposite directions longitudinally of the link and parallel to the direction of stress. Although the releasing action of these fusible links is relatively satisfactory, depending on the low melting point of the alloy used to connect the elements, such links have been found to be inefficient in holding power and incapable of withstanding the required stresses. Consequently the elements separate and release prematurely, and fail to restrain the devices they are intended to control.

The main object of the invention is to provide fusible links of the push and pull types which are constructed so as to be capable of sustaining their intended burden without unintended or premature release or separation of the elements constituting the links, notwithstanding the use as the element-connecting means of alloys of low melting points not inherently capable of withstanding the tensile stresses imposed upon them when embodied in said fusible links.

Another object is to provide fusible links exceedingly small in size and area, but having the capacity to resist relatively great tensile strain and to sustain relatively great pressure without premature or unintended separation of the elements.

Another object is to provide a construction capable of instantaneous release of the elements when the alloy connecting the elements is subjected to heat. This result is accomplished by employing a quick heat transmitting element in combination with a stress bearing element.

2

Other objects and advantages will appear from the following description.

In the drawing:

Fig. 1 is a plan view of my pull type fusible link which may also be used as a push type link, and Fig. 2 is a plan view of one of the two identical elements comprising said link.

Fig. 3 is a plan view of a push type fusible link which may also be used as a pull type link, and Fig. 4 is a plan view of one of the two identical elements comprising said link.

Figs 5, 7 and 9 are plan views, respectively, of modified forms of push type fusible links, and Figs. 6, 8 and 10 are plan views, respectively, of one of the two identical elements comprising the links shown in Figs. 5, 7 and 9.

Fig. 11 is an elevational edge view of the link shown in Fig. 1, and Fig. 12 is an elevational edge view of the link shown in Fig. 5.

Referring to that embodiment of the invention shown in Figs. 1 and 2, the fusible link there shown as a pull type link comprises identical elements 10 and 11 in the form of flat pieces of metal, such as brass or other suitable material, each having one straight longitudinal edge, and superposed in such manner that the straight edges are located at opposite sides of the assembled device. The pointed portions 12, 13, 14 of the element 10 are at one longitudinal side and the pointed portions 15, 16, 17 of the member 11 are directed toward the other longitudinal side of the link. When thus superposed and connected, the elements 10 and 11 form two openings 18, 19, through which extend S-hooks or other stress exerting means 20, 21, respectively. In these figures, the means 20, 21 are shown in section. They may be of various forms and are designed to be connected to the safety devices intended to be controlled. The overlapped portions of the elements 10, 11 are connected together by low melting point solder, indicated at 46 in Fig. 11.

When heat melts the solder, the elements 10, 11 separate by movement laterally in opposite directions substantially at right angles to the directions of stress. This lateral movement of the elements 10, 11 is due to the action of the stress exerting means 20, 21 sliding along and bearing on the edges 22 of the element 10 and the edges 23 of the element 11, as said means 20, 21 pull in opposite directions away from each other. The edges 22, 22 and 23, 23 are diagonally disposed relatively to the direction of stress imposed on the link. The edges 22 of the element 10 are divergent with respect to each other, as are also the edges 23 of the element 11 with respect to each other.

The fusible link shown in Fig. 3 comprises two identical elements 24, 25, one of which is shown detached in Fig. 4. The elements are superposed

and connected together as explained in connection with the link of Fig. 1. The elements 24, 25 are similar in form to the elements 10, 11, excepting that the pointed portions 26 and 27 are shorter than the corresponding parts of the previously described link and consequently overlap to a lesser degree. As indicated by the positions of the stress exerting means 20, 21, bearing against the divergent edges 28, 29 of the respective elements 24, 25, the link as shown is a push type link in which the overlapped portions 26, 27 bear a minimum of the holding burden, but this link could be employed as a pull type of link if desired. When the solder melts, the elements 24, 25 move in opposite side-wise movements due to the bearing pressure of the means 20, 21 as they slide on the edges 28, 29.

The push type link shown in Fig. 5 is relatively small in size and area and is well adapted to be embodied in devices providing limited space. The link comprises elements in flat plate form, indicated at 30, 31, arranged in superposed relation and held together by low melting point solder, indicated at 47 in Fig. 12. The pressure exerting means 20, 21 bear against the divergent edges 32, 33 of the respective elements 30, 31. When the solder melts said elements separate and move sidewise due to the pressure exerted by said means 20, 21 against the edges 32, 33. The link shown in Fig. 5 cannot be employed as a pull type link as can the links of Figs. 1 and 3.

The push type link of Fig. 7 comprises two identical elements such as shown at 34, 35, one of which is shown detached in Fig. 8. Said elements have diagonal edges 36, 37, respectively, against which the stress exerting means 20, 21 bear.

The elements 34, 35 resemble those indicated at 38, 39 heretofore described, and in addition are provided with bent edges 38, 39, which in the assembled link turn upwardly and downwardly, respectively. The edge of one element serves as an abutment for the straight longitudinal edge of the other element and enhances the holding power of the fusible connecting means between the elements without interfering with the separation of said elements when the fusible means becomes melted.

Fig. 9 shows another form of push-type link comprising identical elements 40, 41, having diagonal edges 42, 43, respectively, and end members 44, 45 which provide additional overlapping area for solder connection. The members 20, 21, exerting pressure against the diagonal edges 42, 43, cause the elements 40, 41 to move apart by side-wise or lateral movement when the solder melts under influence of heat. While the end members 44, 45 increase the holding power of the element connecting material, they do not interfere with the separation of the elements when the said material is subjected to heat.

The two elements which comprise each of the aforesaid forms of fusible links may be of equal thicknesses, as shown in the edge view, Fig. 11, or they may be of different thicknesses as shown in the edge view of Fig. 12. The elements composing the link must be of sufficient thickness to provide required strength to prevent buckling in the push type and breaking in the pull type of link. By making one of the elements extremely thin, its heat transmitting capacity is increased and speeded, and the other element can be made of sufficient thickness to sustain the stresses imposed upon the link as a whole. Thus extremely quick releases are obtained under influence of heat without premature or unintended separa-

tion of the elements. This feature of construction, shown in Fig. 12, may be embodied in the several forms of links disclosed, either the push or pull type.

In the drawing, the push type links of Figs. 5, 7 and 9 each comprise two sets of intersecting edges such as the edges 32-33, 36-37 and 42-43, but it should be understood that the links could be straight edged at one end and have the intersecting edges only at the other end. In such case, the stress exerting means 20, for example, could function as heretofore explained by bearing against said intersecting edges, and the stress exerting means 21 would serve as restraining means for holding the elements stationary until permitted to separate by the melting of the fusible material under influence of heat.

Prior art fusible links which comprise separable elements to which hooks or other pull exerting means are fastened, are objectionable because the said hooks or other stress exerting means are not released from the elements when they separate, and consequently the separated elements are carried with the stress exerting means and frequently interfere with the complete release and proper functioning of the safety devices controlled thereby and intended to be released. In the devices of my invention, the stress exerting means 20, 21, regardless of their nature or form, detachably and releasably engage the link elements, and when the latter separate as described herein, said means 20, 21 are released also and their intended functions cannot be interfered with by any connection with the elements of the link.

In referring to the "direction of stress" imposed on the links, I refer to the direction parallel to or aligned with the longitudinal dimension of the link, such stress being imposed by the means 20 and 21 pulling away from each other as in the pull type or pressing toward each other as in the push type of link. My experiments have shown that prior art links in which the elements separate by moving in the direction of stress do not have the holding power which I have attained in my link wherein the elements separate by moving laterally of the direction of stress. Consequently, I have been able to employ alloys of very low melting point, such as 130° F., without premature release of the elements while being subjected to substantial stress. Prior art devices employing 163° F. fusible material have less holding power than the links of my invention employing substantially lower melting point alloys such as the 130° F. fusible material referred to. It is believed that this increase in holding power is due to the distribution of stress in the link in lateral directions relatively to the direction of imposition of the stress, and consequent relieving of the link from the straight longitudinal pull or push imposed by the means 20 and 21. To be able to use low melting point fusible material for connecting the elements while at the same time maintaining the required holding power to withstand substantial stresses is a feature of great value in obtaining quick release of safety devices controlled by the link without premature or unintended release of the elements.

Changes may be made in the form and details of construction of the elements of my device without departing from the scope of the invention as set forth in the appended claims.

I claim:

1. A fusible link comprising two separable elements, a layer of fusible material between said

elements connecting them together in superposed relation, each element having two edges extending at angles other than right angles to the direction of stress imposed on the link, each of said edges of one element intersecting one of said edges of the other element, and means detachably engaging said edges at their intersecting points and exerting stress on said link in opposite directions whereby said engaging means slide along and bear against said edges and said elements are caused to move bodily laterally of the direction of stress when said fusible material melts under influence of heat.

2. A fusible link comprising two separable elements, one of said elements being a quick heat transmitting element of less thickness than the other, a layer of fusible material between said elements connecting them together in superposed relation, each element having two edges extending at angles other than right angles to the direction of stress imposed on the link, each of said edges of one element intersecting one of said edges of the other element, and means detachably engaging said edges at their intersecting points and exerting stress on said link in opposite directions whereby said engaging means slide along and bear against said edges and said elements are caused to move bodily laterally of the direction of stress when said fusible material melts under influence of heat.

3. The fusible link defined by claim 1, in which each of said elements is provided along one longitudinal edge with a bent portion which serves as an abutment for the opposite edge of the other element.

4. A fusible link comprising two separable elements, a layer of fusible material between said elements connecting them together in superposed relation, and means detachably engaging said elements and exerting stress on said link in opposite directions, said elements when connected presenting divergent bearing surfaces to said stress exerting means whereby said elements are caused to move bodily laterally of the direction of stress imposed on said link, when said fusible material melts under influence of heat, said stress exerting means becoming disengaged from said elements when said elements have moved from superposed relation.

5. A fusible link comprising two separable elements, one of said elements being a quick heat transmitting element of less thickness than the other, a layer of fusible material between said elements connecting them together in superposed relation, and means detachably engaging said elements and exerting stress on said link in opposite directions, said elements when connected presenting divergent bearing surfaces to said stress exerting means whereby said elements are caused to move bodily laterally of the direction of stress imposed on said link, when said fusible material melts under influence of heat, said stress exerting means becoming disengaged from said elements when said elements have moved from superposed relation.

6. The fusible link defined by claim 4, in which each of said elements is provided along one longitudinal edge with a bent portion which serves as an abutment for the opposite edge of the other element.

7. A fusible link of the push or pull type comprising two separable elements, a layer of

fusible material between said elements connecting them together in superposed relation, each element having at one of its sides two pairs of converging edges, each of said edges of one element intersecting one of said edges of the other element and forming a pair of openings in the link, and means in said openings detachably engaging said edges at their intersecting points and exerting stress on said link in opposite directions, whereby said engaging means slide along and bear against said edges and said elements are caused to move laterally of the direction of stress when said fusible material melts under influence of heat.

8. A fusible link of the push or pull type comprising two separable elements, one of said elements being a quick heat transmitting element of less thickness than the other, a layer of fusible material between said elements connecting them together in superposed relation, each element having at one of its sides two pairs of converging edges, each of said edges of one element intersecting one of said edges of the other element and forming a pair of openings in the link, and means in said openings detachably engaging said edges at their intersecting points and exerting stress on said link in opposite directions, whereby said engaging means slide along and bear against said edges and said elements are caused to move laterally of the direction of stress when said fusible material melts under influence of heat.

9. A fusible link of the push type comprising two separable elements, a layer of fusible material between said elements connecting them together in superposed relation, each element having an edge extending at an angle other than a right angle to the direction of stress imposed on the link, said edge of one element intersecting said edge of the other element, restraining means releasably bearing on one end of the link, and means releasably engaging said edges at their intersecting point and exerting stress on said link whereby said engaging means slide along and bear against said edges and said elements are caused to move laterally of the direction of stress when said fusible material melts under influence of heat.

10. A fusible link of the push type comprising two separable elements, one of said elements being a quick heat transmitting element of less thickness than the other, a layer of fusible material between said elements connecting them together in superposed relation, each element having an edge extending at an angle other than a right angle to the direction of stress imposed on the link, said edge of one element intersecting said edge of the other element, restraining means releasably bearing on one end of the link, and means releasably engaging said edges at their intersecting point and exerting stress on said link whereby said engaging means slide along and bear against said edges and said elements are caused to move laterally of the direction of stress when said fusible material melts under influence of heat.

11. The fusible link defined by claim 10, in which each of said elements is provided along one longitudinal edge with a bent portion which serves as an abutment for the opposite edge of the other element.

WILLIAM L. ROESSNER.
